DESIGN FOR A ROLLER SKATE

James S. Yuill, Prince Albert, Saskatchewan,
Canada

Application October 2, 1942, Serial No. 108,398

Term of patent 7 years

To all whom it may concern:

Be it known that I, James S. Yuill, a subject of the King of Great Britain, residing at Prince Albert, in the Province of Saskatchewan and Dominion of Canada, have invented a new, original, and ornamental Design for a Roller Skate, of which the following is a specification, reference being had to the accompanying drawing, forming part thereof.

Figure 1 is a side elevational view of a roller skate showing my new design.

Figure 2 is a top plan view.

Figure 3 is a front elevational view, and

Figure 4 is a rear elevational view.

I claim:

The ornamental design for a roller skate, as shown.

JAMES S. YUILL.
